UNITED STATES PATENT OFFICE.

ALBERT P. SOLLENDER, OF CHICAGO, ILLINOIS.

COMBUSTION-PROMOTING DEVICE.

1,324,281.

Specification of Letters Patent.

Patented Dec. 9, 1919.

Application filed December 26, 1917. Serial No. 208,813.

To all whom it may concern:

Be it known that I, ALBERT P. SOLLENDER, a citizen of the United States, residing at Chicago, in the county of Cook and State of Illinois, have invented certain new and useful Improvements in Combustion - Promoting Devices, of which the following is a specification.

My invention relates to improvements in devices for enhancing the power-value of combustible mixtures in internal combustion engines.

One of the objects of my invention is to provide means for indirectly utilizing some of the heat exhausted from the cylinder of an engine for improving the combustible qualities of the fuel charge of engines of this character.

Another object of my invention is to provide means, automatically operable, for introducing ancillary charges of relatively, rapidly combustible fluids into the cylinders of engines to promote the combustible activity of the power charge by shortening the flame-time of combustion of the charge, or the decrease of duration of time within which to complete combustion.

Other objects of my invention are to generally improve devices of this character whereby the ancillary charge, to be taken into the cylinder, to accelerate the time of inflammation of the power charge is accomplished automatically, preferably, by the suction effect of the engine.

Other and further objects of my invention will become readily apparent, to persons skilled in the art, from a consideration of the following description when taken in conjunction with the drawings, wherein:

Figure 1 is a side elevation of an internal combustion engine showing my device connected thereto.

Fig. 2 is a longitudinal central section through the device.

Fig. 3 is a cross section, taken on line 3—3 of Fig. 2.

In all the views the same reference characters are employed to indicate similar parts.

The propagation of the flame, or the complete inflammation of the usual combustible power-charge, in the cylinder of an internal combustion engine, is relatively slow, unless compressed to a high degree, in which event the expansion activity is enhanced, but under such conditions pre-ignition of the charge is liable to occur, thereby depreciating the

power value of the charge, to a greater extent than the advantages afforded by the high compression. The expansion effect of such a charge, if the charge be "fired" or heated to the kindling point at many places throughout its volume, will tend to increase the power-value of the charge by rendering more complete combustion in a given time; but such a procedure is rendered practically inexpedient by the introduction of complication into the mode of operation.

In my invention I automatically introduce into the cylinder of an engine, with the power charge, an ancillary charge composed, in part, of an aqueous vapor accompanied by a component of oxygen which mixes with the carbon of the power charge to form a powerful explosive compound. This gas combines with a larger quantity of oxygen than any other and its combustion, when mixed with oxygen, produces a more intense heat than is afforded by the usual combustible material. Being lighter than the gas composing the major charge of the engine, and its particles being of superior mobility, it readily and quickly mixes with the power charge, the effect of which is to shorten the period of time necessary for complete combustion of the power charge and to enable the charge to absorb the excessive carbon that would otherwise be present in the power charge and be liberated and deposited as free carbon upon the valves and other working parts within the cylinder of the engine.

In the drawings, I have shown one embodiment of my invention, in which 5 is an engine of the internal combustion type, 6 is the intake manifold, 7 is the exhaust manifold, 9 is a part of the water circulating system and 10 is a carburetor, all of which are common in engines of this general character. The device 12, shown in enlarged detail in Fig. 2, consists of an elbow 13, for insertion in the intake manifold, a tube 14, in which a valve 15 is yieldingly held seated by a spring 16. The valve is preferably conical and closes both of the ports 17 and 18, by the resilient effect of the spring 16. One or more perforations 19, open to the atmosphere, are provided in the tube portion 14, between the ports 17 and 18, for admission of air. A conduit tube 20 is connected onto the lower end of the tube 19 by a coupling nut 21. This tube is wound around the exhaust pipe, as at 22, to heat the water content. The tube 20 is provided with a valve

23 that is controllable by a rod 24 extending to the instrument board of an automobile, and is adapted to be manually manipulated. The heat from the exhaust products of combustion that pass through the manifold 7, and out through the pipe 7' evaporates the water, circulating in the pipe 20, thereby producing a vapor, which is taken into and through the conduit 25 provided by the combustion promoting device.

The pressure in the water circulating system increases somewhat, proportional to the speed of the engine, by increased speed of the water circulating pump. This increased pressure tends to compensate for the decrease in the suction effect, due to the increased opening of the throttle valve of the carburetor 10, when the engine is running at a relatively high speed, so that the tendency within the pipe 20 toward opening the valve 15 is substantially constant and the effect of the spring is substantially uniform.

When the suction effect, due to the inspiration stroke of the engine, opens the valve 15, vapor or steam will pass through the pipe 20; through the ports 17 and 18, into the tube 14, and from thence through the conduit 25 into the manifold 6. At the same time air will enter the ports or openings 19 and be drawn through the ports 17-18 mixing thoroughly with the hydrogen gas coming through the tube 20, before it enters the manifold 6, there to be brought into contact with the inwardly moving power charge 35 which now contains the gases or fluids of the ancillary charge. The latter charge takes up a part of the carbon of the power charge in the manifold 6, and is distributed throughout the power-charge within the cylinder of the engine by a process of transpiration, rendering the power charge much more inflammable than otherwise and therefore shortening the time of complete combustion of the power charge.

Imperical demonstration has confirmed the conclusion that if the time required for complete combustion of the power charge is shortened, and thereupon all of the fuel is consumed, that the expansion, produced by the increased temperature, will be greater and the power efficiency of the fuel correspondingly increased.

The quantity of water to be evaporated and to form a constituent part of the ancillary charge, may be varied by the manual operation of the valve 23, through the instrumentality of the rod 24 from the driver's seat in the automobile, and by the same means the water may be entirely shut off, if desired, as when starting the engine.

The strength of the spring 16 may be varied by the threaded part of the tube 14 and the part 27 of the elbow, and secured in adjusted position by the check nut 26.

While I have herein shown and described

a single embodiment of my invention, for the purpose of clear disclosure, it is manifest that changes may be made in the structure within the scope of the appended claims.

Having described my invention, what I claim is:—

1. A device of the character described including in combination, a conduit adapted to be connected to the water circulating system, of an internal combustion motor at one end and the intake manifold thereof at the other end, an intermediate part of said conduit being adapted to be subjected to the heat of the products of combustion of said motor, a fitting interposed in said conduit between the point of application of heat and the end which connects to the intake manifold, said fitting having an opening extending axially therethrough and having a pair of valve seats spaced apart at one end with openings leading to the atmosphere opening into said axial opening between said spaced valve seats, a single valve fitting both valve seats and resilient means for normally holding said valve on its seat.

2. A device of the character described including in combination, a conduit adapted to be connected to the water circulating system, of an internal combustion motor at one end and the intake manifold thereof at the other end, an intermediate part of said conduit being adapted to be subjected to the heat of the products of combustion of said motor, a fitting interposed in said conduit between the point of application of heat and the end which connects to the intake manifold, said fitting having an opening extending axially therethrough and being shaped at one end to provide a pair of valve seats of different diameters spaced apart axially of said fitting, said fitting being provided with openings leading to the atmosphere and communicating with said axial opening between said spaced apart valve seats, a single elongated valve member fitting both valve seats and resilient means for normally holding said valve on its seat.

3. A device of the character described including in combination, a conduit adapted to be connected to the water circulating system, of an internal combustion motor at one end and the intake manifold thereof at the other end, an intermediate part of said conduit being adapted to be subjected to the heat of the products of combustion of said motor, a fitting interposed in said conduit between the point of application of heat and the end which connects to the intake manifold, said fitting having an opening extending axially therethrough and being shaped at one end to provide a pair of valve seats of different diameters spaced apart axially of said fitting, said fitting also having openings leading to the atmosphere and com-

municating with said axial opening therein between said valve seats, an elongated conical valve member fitting both said valve seats and resilient means for normally holding said valve members on its said seat.

5. An article of manufacture including a length of tubing adapted to be connected at one end to the water circulating system of an internal combustion motor and part of 10 which is adapted to be located adjacent the exhaust pipe so that the contents thereof will be subjected to the heat of exhaust gases, a fitting to which the other end of said tubing is connected and an elbow connected to the other end of said fitting adapted for connection to the intake manifold of 15 said internal combustion engine, said fitting having a bore of relatively large diameter extending for a considerable part of the 20 length thereof and then having a compara-

tively short bore of a reduced diameter and then another bore communicating therewith of a still further reduced diameter, this last mentioned bore communicating with said tubing, the reducing of said bores providing 25 a pair of valve seats spaced apart, said fitting also having a plurality of openings 30 adapted to communicate with the atmosphere, the inner ends of which communicate with said fitting between said spaced apart valve seats, a conical shaped valve member adapted to fit both of said seats at the same time and resilient means within said larger bore to normally hold said valve on said seat, said valve being responsive in 35 movement to engine suction.

In testimony whereof I hereunto set my hand.

ALBERT P. SOLLENDER.
